UNITED STATES PATENT OFFICE.

ALLEN S. WISE, OF NEW YORK, N. Y., ASSIGNOR TO WESTINGHOUSE ELECTRIC & MANUFACTURING COMPANY, A CORPORATION OF PENNSYLVANIA.

WRINGER.

Application filed June 17, 1924. Serial No. 720,529.

My invention relates to wringers and it has special relation to power-driven wringers. It pertains to devices of the type disclosed in my copending applications, Serial No. 707,801, filed April 21, 1924, and Serial No. 715,104, filed May 22, 1924, and assigned to the Westinghouse Electric and Manufacturing Company.

An object of my invention is to provide a wringer adapted to fold into a cabinet and to occupy a minimum amount of head room therein.

Another object of my invention is to provide a swinging, folding and detachable wringer.

A further object of my invention is to provide a drive mechanism for a wringer comprising a pair of aligned shaft sections which may be disaligned, and, when disaligned, render the roll drive inoperative.

A still further object of my invention is to provide a gravity clutch for coupling a pair of drive shafts in driving relation for driving a wringer.

A still further object of my invention is to provide a mechanism for supporting a wringer for movement from an elevated to a lower inverted position.

A still further object of my invention is to provide a release mechanism for wringer rolls which is adapted to permit unlimited separation of the rolls and which may be reset without tension adjustment.

Other objects and advantages will appear as the description proceeds.

In the accompanying drawings,

Figure 1 is an elevational view of a combined washing machine and wringer embodying my invention, a wall of a washing machine cabinet being broken away to reveal interior construction.

Fig. 2 is a vertical sectional view of the embodiment illustrated in Fig. 1, a collapsed position of parts being shown in full lines and an operating position being shown in dot-and-dash lines.

Fig. 3 is a view, partially in elevation and partially in section, of the wringer shown in Figs. 1 and 2.

Fig. 4 is a sectional detail view taken on the line IV—IV of Fig. 3.

Fig. 5 is an end elevational view of the wringer, the adjacent portion of the cabinet being broken away.

Fig. 6 is a view similar to Fig. 5 but illus-

trating the wringer in full lines in tilted position and a portion thereof in dot-and-dash lines in a position it goes through in its detachment.

Fig. 7 is a sectional view on the line VII—⁶⁰ VII of Fig. 5, and

Fig. 8 is a sectional detail view of a sleeve.

Figs. 9 to 14 inclusive, are diagrammatic views illustrating successive positions the wringer goes through in passing from a wringing position to a folded position and also to detachment.

In the embodiment illustrated, a cabinet 1 is provided having the end of tub 2 received therein and wringer 3 detachably secured and mounted for downward movement in a manner that will be presently described. The invention, however, is not limited to the specific cabinet and tub but is applicable to ⁷⁰ cabinets and tubs of various types.

On a brace 4 in the cabinet 1, a bracket 5 is mounted, (Fig. 5) having a lug 6 thereon and constituting a support for a plate 7 secured thereto by a hinge 8. The plate 7 ⁸⁰ has a notch 10 therein adapted to permit hinged movement of the plate 7 past the lug 6. The plate 7 also has a lug 11 thereon and is rigid with a sleeve 12. A lower drive-shaft section 13 is rotatably mounted in the bracket 5 and is rigid with a clutch member 14. (Fig. 3) adapted to cooperate with a gravity-actuated clutch member 15 keyed ⁸⁵ for sliding movement on an upper shaft section 16 in the sleeve 12. A projection 17 on the sleeve 12, received in an annular recess 18 in the clutch member 15, limits its sliding movement and retains it in the sleeve 12. A ⁹⁰ tubular support 20 for a wringer frame 21 surrounds the sleeve 12 and has a flange 22 ⁹⁵ thereon adjacent to the plate 7. The flange 22 has a notch 23 therein, adapted, in different positions of the wringer 3, to permit movement of the flange 22 past the lugs 6 and 11, as will presently be described. A ¹⁰⁰ manually controllable latch 24, urged by a spring 25, is pivoted on the support 20 and extends, at one end, through an opening 26 therein, into one of four recesses 27 in the sleeve 12.

The wringer 3 may be swung about the upper shaft section 16 as an axis and may be retained in any one of four vertical positions ¹⁰⁵ 90° apart by the latch 24 cooperating selectively with one of the recesses 27. One of ¹¹⁰

the positions is shown in Fig. 1 wherein the wringer 3 is illustrated as parallel to the plane of the adjacent side of the cabinet. Fig. 9 illustrates this position of the wringer 3 diagrammatically without a showing of the cabinet.

When the wringer 3 is in any of the four principal positions, it can not be moved upwardly, since the notch 23 is spaced laterally away from the lug 11, and the lug 11 will prevent upward movement of the flange 22, as is apparent from Figs. 7 and 9.

If it is desired to fold the wringer 3 downwardly, the tub 2 is removed, in a manner described in the aforementioned application, Serial No. 707,801, and the wringer is swung about a vertical axis to bring the notch 23 immediately below the lug 11 and in registry with the notch 10. This position is shown in Fig. 10. It may then be moved about the hinge 8, to the position shown in Fig. 11, the notches 10 and 23 permitting the flanges 7 and 22 to pass the lug 6. Fig. 6 shows the position of parts after the flange 22 has passed the lug 6 and the wringer has again been slightly turned about the shaft section 16 as an axis. The wringer may be lowered to a completely inverted position, as shown in full lines in Fig. 2 which illustrates a collapsed position of washing-machine parts disclosed in the aforementioned application, Serial No. 707,801 the specific features of which are not essential to this invention. Fig. 14 shows this position of the wringer diagrammatically.

If, instead of folding, it is desired to remove the wringer, it is moved on the hinge 8 until the flange 7 is higher than the lug 6. (Fig. 11) then the wringer 3 is rotated about the upper shaft section 16 as an axis until the notch 23 is beneath the lug 11, (Fig. 12). It may then be drawn upwardly, the tubular support 20 sliding on the sleeve 12 until it is entirely removed (Fig. 13).

A reverse movement of the wringer 3 will restore it to locked relation with respect to the plate 7 and the sleeve 12. To return it to up-right position, it is then rotated until the notches 23 and 10 are in registry, whereupon it is moved upwardly about the hinge 8. Rotation of the wringer about the upper shaft section 16 as an axis will then cause the flange 22 to move under the lug 6 and lock the wringer in place.

On the movement of the wringer 3 into elevated position, the upper clutch member 15 is permitted to slide downwardly and to engage with the lower clutch member 14, thus coupling the shaft sections 13 and 16 in driving relation.

The wringer 3 is provided with a roll-release mechanism.

The upper shaft section 16 is connected, by a manually-controlled roll-reverse mecha-

nism 28 of conventional construction, to the shaft 30 of a roll 31. A gear 32 on the shaft 30 meshes with a gear 33 on the shaft 34 of an upper roll 35. The shaft 34 is journaled in bearing blocks 36.

A bar 37 extends longitudinally of the wringer 3 and rests upon the upper surfaces of the bearing blocks 36 for transmitting pressure to the rolls, and a strap 38 extends from the bottom of one of the bearing blocks 36 upwardly and longitudinally of the wringer 3 above the bar 37, to which it is secured at points 40, and again downwardly, terminating below the other bearing block 36.

A pair of lugs 41 are outwardly directed from the frame 21 and are engaged by a pair of plates 42 which are connected by a web 43 and by a roller 44 positioned between the strap 38 and the bar 37. A spring 45 engages, at one end, the strap 38 and surrounds a rod 46 extending therefrom to the web 43 against which the other end of the spring 45 abuts. A nut 47 on the rod 46 engages the other face of the web 43. The roller 44 is adapted to rest against a cam 48 which also cooperates with a similar roller 50 and parts on the other end of the wringer similar to those described. The cam 48 is rigid with a spindle 51 journaled in an opening in the strap 38 and secured to a control bar 52.

When the parts are in wringing position, as shown in Fig. 3, the force of the spring 45 tends to swing the web 43 and the plates 42 about the roller 44 as an axis but the engagement of the plates 42 with the lugs 41 causes the force of the spring to be directed downwardly for exerting pressure on the rolls 31 and 35.

To release the rolls, the operator strikes the control bar 52, thus rotating the cam 48 and permitting the roller 44 to move towards the spindle 51. This removes the downward urge of the spring 45 upon the bar 37, withdraws the ends of the plates 42 from the lugs 41, as illustrated by dot-and-dash lines in Fig. 1, and permits substantially instantaneous upward movement of the roll 35 and the bearing blocks 36 in the frame 21. If desired, the upper roll 35 and the entire release mechanism may be lifted out of the top of the wringer frame 21. This facilitates cleaning of parts.

When the cam 48 is in the release position, the ends of the plates 42 may be positioned below the lugs 41. To reset the mechanism after its release, the operator imparts rotative movement to the control bar 52 and causes the cam 48 to move the rollers 44 and 50 outwardly. This brings the ends of the plates 42 upwardly against the lugs 41 and puts the spring 45 and the rolls 36 and 31 under compression. The restoration of the rolls to the original pressure is thus accomplished without tension adjustment.

The position of the spring 45 is such that very little room is taken up above the rolls.

By providing a drive shaft in two alignable, relatively movable sections, a need for special hinging or pivot mechanism in the neighborhood of the reversing mechanism is obviated. This feature, together with the compact arranging of the spring 45 and associated parts, results in a conservation of space, as the wringer requires very little room in the cabinet.

The invention is not limited to the specific details of construction and operation of the embodiment illustrated which may be extensively modified and varied. For instance, instead of the wringer illustrated and described many wringers of the prior art might be used in connection with the dis-alignable shaft features. Again the release mechanism is of general application and may be used independently of other features of the device. A substantial range of equivalents is contemplated within the spirit of the invention and scope of the appended claims.

I claim as my invention:

1. In a power-driven wringer, the combination with a vertically-extending power-driven shaft section, a clutch member mounted on the upper end of the shaft section, a bracket for supporting said power-driven shaft section, a wringer including a frame, a tubular support for the wringer and hinge means pivotally supporting the wringer and tubular support on the bracket and permitting the wringer, frame and tubular support to swing on a horizontal axis from an upper operating position to a lower inoperative position, of a shaft section operatively connected to the wringer and extending through the tubular support, and a gravity-actuated

clutch member on the last named shaft section effective to couple the two shaft sections in driving relation upon movement of the wringer, frame and support from their inoperative position to their operative positions.

2. The combination of a support, a shaft section extending through said support, a second shaft section, a support for the first mentioned support, the first mentioned support and the first mentioned shaft section being movable with respect to the second support into operative and nonoperative positions, means for coupling said sections in drive relation when said first mentioned support and said first mentioned section are in operative position, and means for securing said first mentioned support in operative position, said means being releasable by the rotation of said first mentioned support with respect to said second support.

3. The combination of a wringer having a pair of wringer rolls, a shaft section for driving said rolls, a second shaft section, a coupling for maintaining said sections in driving relation, a fixed support having a lug thereon, a member hinged to said support and having a slot adapted to receive said lug on the movement of said member, a lug on said member, a second support rigid with said wringer and a flange on said second support having a slot therein adapted to receive either of said lugs, said second support being movable to position said flange in locked relation to said lugs, whereby said second support is detachably secured to the first mentioned support and said member.

In testimony whereof, I have hereunto subscribed my name this 27th day of May, 1924.

ALLEN S. WISE.
